UNITED STATES PATENT OFFICE.

JAMES WALTON, OF PHOENICIA, NEW YORK.

ELECTRIC FLASHER.

1,268,652.

Specification of Letters Patent. Patented June 4, 1918.

Application filed June 13, 1917. Serial No. 174,487.

To all whom it may concern:

Be it known that I, JAMES WALTON, a citizen of the United States, and a resident of Phoenicia, in the county of Ulster and State 5 of New York, have invented a new and Improved Electric Flasher, of which the following is a full, clear, and exact description.

This invention relates to electric signs of the flasher type, and it deals particularly 10 with means for automatically opening the electric circuit of the sign lamps at any predetermined time.

The invention has for its general objects to improve the construction and operation of 15 apparatus of this character so as to be reliable and efficient in use, comparatively simple and inexpensive to manufacture, and so designed that the time for cutting out the sign can be easily and quickly adjusted.

20 A more specific object of the invention is the provision of a novel combination of flasher and cut-out switches which are operated by an ordinary alarm-clock mechanism, whereby one of the gear wheels can be used 25 to operate the flasher switch and the hammer of the alarm can be used for operating the cut-out switch.

With such objects in view, and others which will appear as the description proceeds, the invention comprises various novel 30 features of construction and arrangement of parts which will be set forth with particularity in the following description and claims appended hereto.

35 In the accompanying drawings, which illustrate one embodiment of the invention and wherein similar characters of reference indicate corresponding parts in all the views,

Figure 1 is an elevation of the clock mechanism and the flasher and cut-out switches operated thereby;

Fig. 2 is a view taken from the left side of Fig. 1;

Fig. 3 is a view of the clock mechanism 45 taken at the opposite side from that of Fig. 1;

Fig. 4 is a detail view of the alarm mechanism which is used for operating the cut-out switch;

50 Fig. 5 is a diagrammatic view of the complete flasher system with the sign in section; and

Fig. 6 is a modification of the means for operating the flasher switch.

65 Referring to the drawings, A designates

the clock mechanism, B the flasher switch, C the cut-out switch and D the sign. The mechanism A is an ordinary alarm-clock, with the exception that the gong is removed and the cut-out switch is substituted. At one 60 side of the casing 1 of the clock is an opening 2, Fig. 3, into which extends a lever 3 which is fulcrumed at 4 on a post 5 rising from the base 6 on which the clock is mounted. The inner end 7 of this lever is disposed 65 in the path of the teeth 8 of a gear wheel 9 of the clock mechanism. In the present instance the lever is engaged by the second gear wheel, so that every second the flash 70 will be made and broken. The lever 3 embodies a contact 10 which forms the movable element of the flasher switch B, the fixed element being a laterally extending finger 11 on the upper end of a post 12 fastened to the base 6, such post being connected in circuit 75 by a wire 13. The outer end of the lever 3 or the movable contact 10 engages under the fixed contact 12, and the fulcrum 4 is so positioned that the movable contact tends to 80 gravitate away from the fixed contact, but the gear wheel 9 oscillates the lever and causes the contact 10 to move rapidly into and out of engagement with the contact 11.

The circuit cut-out switch C embodies a plate or block of insulation 14 on which is 85 a fixed contact 15 and a movable contact 16 pivoted at 17. The movable contact 10 on the flasher switch B is connected by a wire 18 with the lever 16 which forms the movable contact of the switch C. The lower end of 90 the lever 16 has a laterally extending lug 19 disposed adjacent the alarm hammer 20 of the clock, so that when the alarm device of the clock "goes off" the hammer strikes the lever 16 and separates it from the contact 15, 95 so that the circuit of the sign D is thereby opened. The fixed contact 15 of the cut-out switch is connected by a wire 21 which leads to one terminal 22 of the sign, while the wire 23 connects with the other terminal 24. The 100 wires 13 and 23 may be connected with a battery or other source of current E.

The clock mechanism can be stopped at any desired time manually by means of a brake F, Figs. 1 and 2, which is a lever fulcrumed at 25 on the base 6, with one end of the lever forming a finger-piece 26 and the other a shoe member 27 which is adapted to engage the periphery of the balance wheel 28. In Fig. 2 the brake lever is shown in 110

released position, and by operating the finger-piece 26 the lever can be engaged with the balancing wheel 28 to stop the clock.

When the lamps 29 of the sign are lighted, 5 the switch C is closed, and if the clock is not already running the main spring 30 is either wound or the brake lever released from the balance wheel 28. The clockworks are now 10 set in motion and the gear wheel 8 causes the lever 3 to oscillate so that the lamp circuit will be made and broken in quick succession, whereby the sign will flash and dim. If it is desired to automatically cut out the sign at a late hour of the night, for instance, the 15 alarm device 31, Fig. 4, of the clock is set in the usual manner, so that when the proper time arrives the cam-wheel 32 will release the finger 33, so that the catch or stop 34 will disengage the finger 35, which is mounted on 20 the hammer shaft 36. The clock mechanism will now oscillate the hammer 20, so that the cut-out switch will be thrown open.

In the modification shown in Fig. 6 the gear wheel 9 is adjustable longitudinally of 25 its shaft 37, and on the shaft may be arranged one or more wheels 38 which can be adjusted to take the place of the wheel 9, and on the wheel 38 are teeth 39 wider than the teeth 8 on the gear 9, so that the length 30 of the flashes of the sign may be longer. Any number of wheels may be mounted on the shaft 37 to get any desired lengths or periods of flashes.

From the foregoing description taken in 25 connection with the accompanying drawings, the advantages of the construction and method of operation will be readily understood by those skilled in the art to which

the invention appertains, and while I have described the principle of operation, together with the apparatus which I now consider to be the best embodiment thereof, I desire to have it understood that the apparatus shown is merely illustrative and that such changes may be made when desired as 45 fall within the scope of the appended claims.

Having thus described my invention, I claim as new and desire to secure by Letters Patent:

1. The combination of two unitary, self-contained devices, one device being an alarm clock including a casing having an opening, and the other device being a circuit make and break attachment comprising a base on which the clock is mounted, a support on the base, a lever fulcrumed on the support and having an extremity extending into the opening and engaging a gear wheel of the clock whereby the latter oscillates the lever, a contact on the lever, a contact on the base and engageable by the contact on the lever, and a lamp circuit controlled by the contacts. 50

2. The combination of an ordinary alarm clock having an opening in its casing, a support on which the clock is mounted, a post rising from the support, a lever fulcrumed on the post at a point adjacent the opening of the casing and having one extremity extending into the casing to engage a gear wheel of the clockworks within the casing, 55 a fixed contact on the support, a contact carried by the lever and movable into and out of engagement with the first-mentioned contact, and a circuit controlled by the contacts. 65

JAMES WALTON.
